US00D769271S

(12) **United States Design Patent** (10) **Patent No.:** **US D769,271 S**
(45) **Date of Patent:** **** Oct. 18, 2016**

(54) **DISPLAY SCREEN OR PORTION THEREOF WITH GRAPHICAL USER INTERFACE**

(71) Applicant: **Thales Avionics, Inc.**, Irvine, CA (US)

(72) Inventor: **Andrew A. Guesnon, Jr.**, Anaheim Hills, CA (US)

(73) Assignee: **Thales Avionics, Inc.**, Irvine, CA (US)

(**) Term: **14 Years**

(21) Appl. No.: **29/451,669**

(22) Filed: **Apr. 5, 2013**

(51) LOC (10) Cl. **14-04**

(52) U.S. Cl.

USPC **D14/486**

(58) **Field of Classification Search**

USPC D14/485-495; 715/700, 702, 716, 719, 715/726, 733, 763, 765, 781, 783, 810, 835, 715/864

CPC .. G06F 3/0482; G06F 3/0484; G06F 3/0485; G06F 3/0486

(57) **CLAIM**

The ornamental design for a display screen or portion thereof with graphical user interface, as shown and described.

DESCRIPTION

The FIGURE is a front view of a display screen or portion thereof with graphical user interface showing my new design.

The broken lines in the FIGURE represent portions of the display screen or portion thereof with graphical user interface that form no part of the claimed design.

1 Claim, 1 Drawing Sheet
